UNITED STATES PATENT OFFICE.

JAMES C. WEBSTER, OF TOPEKA, KANSAS.

HOTEL KEY CHECK.

Application filed May 9, 1921. Serial No. 467,900.

To all whom it may concern:

Be it known that I, JAMES C. WEBSTER, a citizen of the United States, residing at Topeka, in the county of Shawnee and State of Kansas, have invented certain new and useful Improvements in Hotel Key Checks; and I do hereby declare the following to be a full, clear, and exact description of the invention, such as will enable others skilled in the art to which it appertains to make and use the same.

This invention is an improved key check for use in hotels and other like places, the object of the invention being to provide an improved key check which is cheap and simple in construction, is strong and durable, which may be readily and permanently attached to the shank of a key so that it cannot be detached therefrom without disassembling the parts of the check and which presents surfaces that may be advantageously used for advertising.

The invention consists in the construction, combination and arrangement of devices hereinafter described and claimed.

In the accompanying drawings:—

Figure 1 is a perspective view of a key check constructed in accordance with my invention, showing the same attached to a key.

Figure 2 is a longitudinal sectional view of the same on the plane indicated by the line *a—a* of Figure 1.

Figure 3 is a transverse sectional view of the same.

Figures 4—5 are detail plans of the separated parts of the lock.

Figure 6 is a detail elevation, showing the socket member of the fastener which secures the card between the check members.

My improved key check comprises a pair of blanks or members 1—2 which are here shown as oblong rectangular form but which may be of any suitable shape and may be of any suitable size. Preferably the said members are made of leather but they may be made of any other suitable material, within the scope of my invention. Each of the said members has an opening 3 and a card 4 which is used for advertising, adapted to be placed between the members to display its advertising content or matter through the openings 3. The members are here shown as sewed together at 5, along their side edges and around the inner end, which is formed

with a tab 6, the outer end 7 of the check being open between the members, to permit the insertion and removal of the card 4. Said card when in place is secured by a suitable fastener 8 or by any suitable means. The tab portions of the members are provided with openings 9.

A lock 10 is provided to secure the key to the check and is preferably made of nickel plated sheet metal. This lock comprises a pair of circular disks or plates 11—12 which are identical in construction and which are placed in the openings 9 of the members 1—2 respectively and are secured in said openings by base flanges 13 which bear against the inner sides of said members and outer flanges 14 which are struck up from the key members and constitute U-shaped or peripherally grooved attaching rims which bear around the said openings and on the outer sides of said members 1—2. The member 11 of the lock has a key slot 16 which extends across the center of the bottom thereof and is formed with a central circular enlargement 17. The member 12 has a similar key slot 18 which is formed with a central circular enlargement 19.

The lock members are attached to the check members before the latter are sewed or otherwise secured together at their sides and the key is placed in the slots of the lock members while the said slots register with, and said lock members are so secured to the check members that when the latter are secured together the slots of the check members will be arranged at right angles to each other so that the shank of the key is engaged in the openings formed by the enlargement of the slots and hence the key cannot be removed. The name of the hotel together with its address may be printed on one of the check members just below the lock and the number of a room in the hotel corresponding with the key may be printed in a corresponding place on the other check member.

Having thus described my invention, I claim:—

1. A key, a check, plates to retain the key having elongated openings through which the key is inserted, and said plates being disposable on the check immovable relatively to each other with the key passing through said openings and with said openings disaligned.
2. A key, similar check blanks forming a

card retaining and display pocket, closure means for the pocket, said blanks having openings therethrough, plates to retain the key having openings through which the key is inserted, said plates having peripheral grooves whereby the blanks are attachable in said openings of the plates, and said plates being disposable immovable relatively to each other with the key passing through their openings and with said openings dis- 10 alined.

In testimony whereof I affix my signature in presence of two witnesses.

JAMES C. WEBSTER.
